(57) **CLAIM**

I claim the ornamental design for a display cradle, as shown and described.

DESCRIPTION

FIG. 1 is a perspective view of a display cradle showing the claimed design;

FIG. 2 is a front elevational view of FIG. 1;

FIG. 3 is a rear elevational view of FIG. 1;

FIG. 4 is a side elevational view of FIG. 1; and

FIG. 5 is a side elevational view of FIG. 1 opposite that of FIG. 4;

FIG. 6 is a top plan view of FIG. 1; and,

FIG. 7 is a bottom plan view of FIG. 1.

The broken lines in the drawings represent unclaimed subject matter and form no part of the claim.
